Filed Dec. 13, 1971, Ser. No. 207,719

Term of patent 14 years

Int. Cl. D7—03

U.S. Cl. D54—12

FIG. 1

FIG. 2

FIG. 3

FIG. 4

FIG. 5

FIG. 1 is a perspective view of a spoon showing my new design:

FIG. 2 is a top plan view thereof:

FIG. 3 is a side elevational view thereof:

FIG. 4 is a transverse cross-sectional view through the bowl of the spoon, taken on the line 4—4 of FIG. 2; and

FIG. 5 is a longitudinal cross-sectional view through the bowl and handle, taken on the line 5—5 of FIG. 2.

The characteristic feature of my new design is the bowl portion of the spoon, comprising the arcuate curvature in cross-section, the length, proportions and tapering width of the side flanges and the open ends of the bowl portion.

I claim:

The ornamental design for a spoon or the like, as shown and described.
